DESIGN FOR AN EMBROIDERED TEXTILE FABRIC

William G. Meier, Mamaroneck, N. Y.

Application November 4, 1937, Serial No. 72,608

Term of patent 3½ years

To all whom it may concern:

Be it known that I, William G. Meier, a citizen of the United States of America, residing in Mamaroneck, county of Westchester, and State of New York, have invented a new, original, and ornamental Design for Embroidered Textile Fabric, of which the following is a specification, reference being had to the accompanying drawing, forming part thereof.

The figure on the drawing is a plan view of an embroidered textile fabric showing my new design.

My design is characterized by rows of diamond shaped eyelets, each eyelet being outlined by double rows of contrasting colored embroidery, the areas between the double diamond stripes embodying staggered rows of embroidered dots as shown.

I claim:

The ornamental design for an embroidered textile fabric, substantially as shown and described.

WILLIAM G. MEIER.
